(57) **CLAIM**

The ornamental design for a laser processing machine as shown and described.

DESCRIPTION

FIG. 1. is a front, top and left side perspective view of a laser processing machine showing our new design;

FIG. 2. is a rear, top and right side perspective view thereof;

FIG. 3. is a front view thereof;

FIG. 4. is a rear view thereof;

FIG. 5. is a top plan view thereof, a bottom view is omitted because the article is a heavy object;

FIG. 6. is a right side view thereof; and,

FIG. 7. is a left side view thereof.

The broken lines showing of the laser processing machine is included for the purpose of illustrating portions of the laser processing machine and forms no part of the claimed design.
